PET CANTEEN

Joseph C. Mineo, Los Angeles, Calif.
(6735 Shoup Avenue, Canoga Park, Calif. 91304)

Filed Oct. 19, 1972, Ser. No. 299,150

Term of patent 14 years

Int. Cl. D30—03

U.S. Cl. D30—13

FIG. 1 is a perspective view of a pet canteen showing my new design;

FIG. 2 is a left side elevational view thereof;

FIG. 3 is a top plan view thereof;

FIG. 4 is a front elevational view thereof;

FIG. 5 is a rear elevational view thereof.

I claim:

The ornamental design for a pet canteen, substantially as shown and described.
